FRANCIS LEIGH MARTINEAU, OF LONDON, ENGLAND.

OPERATING MECHANISM OF KITCHEN REVERSING RUDDERS.

1,425,887.

Specification of Letters Patent. Patented Aug. 15, 1922.

Application filed October 27, 1920. Serial No. 419,919.

To all whom it may concern:

Be it known that I, FRANCIS LEIGH MARTINEAU, a subject of the King of Great Britain, and resident of London, England, have 5 invented certain new and useful Improvements in and Relating to the Operating Mechanism of Kitchen Reversing Rudders, of which the following is a specification.

This invention relates to mechanism for 10 operating kitchen reversing rudders that is rudders of the kind forming the subject of British Patent No. 3249 of 1914.

As is well known a Kitchen reversing rudder involves two members adapted to be 15 moved in unison to effect steering and relatively one to the other to control the speed and direction of the travel, the arrangement being such that with the engine working at constant speed and in one direction the ship 20 will proceed ahead as is ordinarily the case when the rudder is full open. As the two leaves of the rudder are closed the propelling effect of the engine is gradually reduced until a position is reached when the 25 engine, although turning, will have the same effort ahead as astern and the ship will remain stationary. Further closing of the rudder will cause the ship to go astern and the maximum effort astern will be produced 30 when the rudder is quite closed.

As a rule the rudders when closed make an angle of 90 degrees with each other. Each rudder therefore has to operate through 45 degrees to reach the fully open 35 position.

As it is usual to operate a rudder through 35 degrees each side of the centre, or 70 degrees in all for steering purposes, each leaf of the Kitchen rudder must be capable 40 of moving 70 plus 45 degrees, or 115 degrees, that is $57\frac{1}{2}$ degrees each side of the centre line and the position when the rudder is full open (i. e., ahead) and in line with the keel will be $57\frac{1}{2}$ less 35 degrees= 45 $22\frac{1}{2}$ degrees forward of the centre line. With the rudder closed (i. e., astern) and in line with the keel it will be 45 less $22\frac{1}{2}$ = 22 $\frac{1}{2}$ degrees aft the centre line.

The object of the present invention is to 50 provide convenient and effective mechanism by which the desired movements can be effected and controlled, and the invention consists broadly in the provision of a pair of variable stroke, or variable delivery or 55 other suitable pumps, each adapted to operate a hydraulic motor operatively con-

nected to a rudder member, and means for controlling the pumps whereby the rudder members can be operated in unison to effect the steering and relatively to effect control 60 of speed and direction of travel.

The control devices comprise essentially devices under the control of the operator for controlling the pumps and means whereby the hydraulic motors automatically throw 65 the pumps out of effective operation when the rudder members have moved to any desired position or relative positions and hold the rudder members in such positions. This automatically operating mechanism is 70 preferably of the floating link or hunting gear type interposed between the pumps and the hydraulic motors.

Figs. 1 and 2 of the accompanying drawings illustrate diagrammatically two methods of carrying out the invention.

In the embodiment of the invention illustrated by Fig. 1, the solid rudder stock 1 is connected to the starboard rudder and is surrounded by the hollow rudder stock 2 80 connected to the port rudder. Those are respectively coupled to the two tillers 3 and 4 one of which therefore operates the starboard rudder, and the other of which operates the port rudder. The starboard tiller 85 3 is connected by means of a connecting rod 7 and pins 5 and 9^a with a twin ram system comprising a ram 9 operating in opposed cylinders 11 and 12. In the same manner the tiller 4 is coupled by means of a connecting rod 8 and pins 6 and 10^a to a second similar twin ram system comprising a ram 10 operating in opposed cylinders 13 and 14.

Each of the two tillers 3 and 4 can therefore be operated independently by their respective hydraulic systems. The ram system associated with one tiller is coupled to one variable delivery reversible hydraulic pump 15 by means of pipes 20 and 22 in such a manner that when the pump is rotated in one direction and the stroke control spindle 18 is pulled outwards from the pump the liquid flow will be from the cylinder 11 by way of a pipe 20 into the pump 15 and through another pipe 22 into the cylinder 12 thus causing one of the rams to move away from the rudder head.

In the like manner the other hydraulic motor system is coupled to the second pump 16 so that when its control spindle 19 is 110 drawn outwards from it, liquid will pass from a cylinder 13 by a pipe 21 to the

pump and be delivered through another pipe 23 to the other cylinder 14, causing the ram 10 of this cylinder to move away from the rudder head.

5. The two pumps are both coupled to and driven at approximately constant speed and continuously by an electric motor or other prime mover 17, or from the main engine or propeller shaft.
10. The control spindle 18 of one of the pumps 15 is connected to a floating lever 24 by a pin 26 at a suitable point between its extremities. One end of it is coupled by a suitable disposed connecting rod 30 and pins 28 and 32 to the ram 9 and this end of the floating lever therefore moves with the ram. The other end of the floating lever is coupled by a connecting rod 36 to a point between the extremities of a second floating lever 38.
15. In like manner the control spindle 19 of the other pump 16 is coupled by pins 27 and 29 and a floating lever 25 one end of which is connected to the ram 10 and therefore moves with it.
20. The other end of the floating lever 25 is connected by a connecting rod 37 to a secondary floating lever 39.
25. The two secondary floating levers 38 and 39 are at one end pivoted by a common pin 42 to a slide 43 guided by a bracket 46 to move in a straight line and having collars 44 and 45 fixed upon it so as to give a defined limited motion.

The other ends of the secondary floating levers 38 and 39 are coupled respectively by pins 47 and 48 and connecting rods 49 and 50 each to the inner arms of a pair of suitably pivoted bell-crank levers 53 and 54. These bell crank levers 53 and 54 are of the same dimensions but oppositely disposed to one another and their outer arms are coupled together by a connecting rod 59 and pins 57 and 58, and are connected by a rod 60 to the steering mechanism on the bridge 45 of the ship.

The centrally disposed spindle or slide 43 is also connected to mechanism adapted to be operated from the bridge to control the speed and sense of motion of the ship.

50. The action of the gear is as follows:— For steering, if the steering rod 59 be considered as operated from the steering wheel so as to move towards to port side, then the inner arm of one of the levers 53 and 54 will move forward and the outer arm of the other lever will move aft by a similar amount. This will cause the control spindle of one of the pumps to be pulled out and control spindle of the other pump 60 to be pushed in. The ram system on one side will move aft until movement of spindle has been restored by operation of its floating lever through its link and the pump is restored to the zero or non-delivery position.
65. The other ram system will at the same time

move forward until zero stroke position of the pump is reached. In other words the two ram systems move in opposite directions a like amount causing the pair of rudders to move as one unit over to starboard or port 70 according to the direction in which the control rod 59 is moved, thus steering the ship in the desired direction.

Steering, and steering alone, is therefore affected by the movement of the operating 75 rod 59 by the steering wheel operated exactly as if operating an ordinary steering gear and rudder.

If, however, the control spindle 43 be moved in a forward direction, then both 80 links move in the same sense and both the pump control members 18 and 19 are pulled out from the pumps causing both ram systems to move aft altering the angular relation between the tillers and closing the rudders.

If the central spindle 43 be moved until the collar 45 aforesaid reaches the bracket 46 then each tiller will have moved through 45 degrees and the rudder will be closed 90 giving the astern position. Control of the central spindle therefore alters the speed of the ship independently of the rudder position for a steering operated by the quarter-master or helmsman. These two functions 95 can be performed at one and the same time, independently and without any interference the one with the other.

In the case of large and powerful installations the slight errors caused by the 100 angularity of the various connecting rods and levers might be a cause of trouble, and in such a case the system can be modified in detail as illustrated by Fig. 2, whilst remaining absolutely similar in principle and 105 action.

In this embodiment of the invention the floating levers are substituted by toothed sectors gearing with sliding racks or worms. The end 61 of the control spindle of the 110 pump 15 slides in a fixed guideway 80, and pivoted thereon is a rocking member 64 constructed at opposite ends to form toothed sectors adapted to engage respectively correspondingly toothed sliding racks 68 and 115 65. The rack 65 is connected by a pin 28 to one end of a connecting rod 30, the other end of this connecting rod being connected by a pin 32 to a projection formed on the ram 9.

A worm or spur wheel 69 is rotatively mounted on the end of the sliding rack 68, and gears at one side with a sliding worm or rack 72 adapted to slide in a fixed standard or bracket 82. The other side of 125 the worm or double sided rack 72 gears with a spur or worm wheel 73 rotatively mounted on a standard or bracket 82, and adapted to gear also with another rack or worm 75 arranged to slide at right angles to the rack or 130

worm 72. The end of the rack or worm 75 is connected by a link 77 to a similar rack or worm 76 arranged to slide in a standard or bracket 83, and the end of the rack or worm 76 is connected by a rod 60 to the steering gear mechanism under the direct control of the operator or steersman.

The rack or worm 76 gears with a spur or worm 74 rotatively mounted on the standard 10 or bracket 83 and adapted to also gear with one side of a worm or double sided rack 71 arranged to slide in the said standard or bracket 83 at right angles to the rack or worm 76. The other side of the worm or rack 71 gears with one side of a spur or worm wheel 70, while the opposite side of this spur wheel gears with the worm or rack 78 connected by the spindle 43 to the reversing and speed controlling mechanism 20 under the direct control of the operator or steersman.

The worm or spur wheel 70 is rotatively mounted on the end of a sliding worm or rack 67 gearing with a toothed sector on one 25 end of a rocking member 63 pivoted on a slide 62 forming or secured to the end of the controlling spindle of a pump 16 adapted to operate the port ram 10 by means of the passages 21 and 23 leading to the ram cylinders 30 13 and 14 respectively.

The other end of the rocking member 63 is formed as a toothed sector gearing with the sliding rack 66 of which the end is connected by a pin 29 to one end of a connected 35 rod 31, the other end of this connecting rod being connected by a pin 33 to a projection formed on the ram 10.

The spur or worm wheels 69 and 70 may be substituted by double ended toothed sectors.

40 The connecting passages between the pumps 15 and 16 and the ram cylinders 11, 12, 13 and 14 are the same as in the plant shown in Fig. 1, and the rocking members 63 and 64 operate in the same manner as the 45 corresponding floating levers 24 and 25 Fig. 1, and the worm or gear wheels 69 and 70 as the corresponding floating levers 38 and 39 Fig. 1.

Various positions of the tiller are indicated at *a*, *b*, *c*, *d* and *e* in Figs. 1 and 2.

a is the position of the starboard tiller when the vessel is going ahead with the rudder at 35° to starboard.

b is the position of the starboard tiller 55 when the vessel is going ahead with the rudder amidship.

c is the position of the starboard tiller when the vessel is going ahead with the rudder at 35° to port.

60 *d* is the position of the starboard tiller when the vessel is going astern with the rudder amidship.

e is the position of the starboard tiller when the vessel is going astern with the rudder at 35° to port.

65

*a*¹, *b*¹, *c*¹, *d*¹, and *e*¹ are the corresponding positions of the rams 9 and 10.

The worms 75, 76 and 78 operated by the control spindles can either be used as racks and given rectilinear axial motion or be 70 mounted so as to have no end motion and be operated rotationally which ever is more convenient. In either case the effect will be similar and as described in connection with the lever example previously given.

75

Constructionally however, the arrangement with worm wheels eliminates errors due to angular motion of the levers, and also gives an arrangement capable of being mounted all on one bedplate as a unit and 80 occupying less space than the lever system.

By using racks, or worms operating as such, adjustments can be easily made by rotating the worm and in like manner wear can be minimized or compensated for by use 85 of a new part of the worm surface.

What I claim and desire to secure by Letters Patent is:—

1. Kitchen rudder operating mechanism provided with starboard and port tiller operating mechanism each consisting of a floating lever connected at one end by a connecting rod to a double ended ram or plunger working in cylinders and adapted to be operated by a variable throw or delivery pump 90 having a controlling spindle connected to a slide carrying the fulcrum of the said floating lever, the other end of the floating lever being connected by a link to the fulcrum of a secondary floating lever of which one 100 end is adapted to be moved by reversing and speed controlling mechanism adapted to be operated directly by the operator, the other end of the secondary floating lever being connected by a link to one arm of a bell 105 crank lever of which the other arm is connected to mechanism operable by steering gear adapted to be operated directly by the operator.

2. Kitchen rudder operating mechanism 110 in accordance with claim 1 wherein the operating arms of the bell crank levers are linked together in such a manner that their transmitting arms move simultaneously in opposite directions and so operate the pump controlling spindles in opposite directions, and wherein both of the secondary levers are pivoted to a common operating rod in such a manner that the transmitting fulcrums of the levers move simultaneously in the same 115 direction and so operate the pump controlling spindles in the same direction.

In witness whereof I affix my signature.

FRANCIS LEIGH MARINEAU.
